Primary Examiner — Robert M. Spear

(57)

CLAIM

The ornamental design for wine cooler, as shown and described.

DESCRIPTION

1. Wine cooler

1.1 : Front

1.2 : Back

1.3 : Left

1.4 : Right

1.5 : Top

1.6 : Bottom

The real item is a bamboo bottle cooler used as a refrigerating container for various beverage bottles such as champagne bottle, wine bottle, sake bottle, soft drink bottle, etc.; by having the opening window in front of the real item, it is possible to easily confirm the label of the bottle and the remaining amount in the bottle.

1 Claim, 6 Drawing Sheets
